ABSTRACT OF THE DISCLOSURE

An improved method of making sulfur-oil slurries for pipeline transportation by evaporation cooling of said slurries prior to introducing said slurries into the pipeline.

The present invention relates to an improved method of making sulfur-oil slurries for pipeline transportation by cooling said slurries prior to injecting said slurries into a pipeline by evaporation cooling with a volatile low molecular weight hydrocarbon such as an aliphatic hydrocarbon having less than 6 carbon atoms.

BACKGROUND OF THE INVENTION

The transportation of sulfur neat or as a water or oil slurry in pipelines is well known in the art as noted by reference to U.S. Pats. 2,798,772; 2,917,345 or 2,947,578 or as described in Pipeline Industry, June 1967, pages 58-60. In making the sulfur into a sulfur-hydrocarbon slurry, the sulfur is generally sprayed in molten form into either water or a hydrocarbon to form a slurry suitable for transportation through a pipeline. Formation of a stable slurry wherein the sulfur does not undergo any undesirable change or the slurry does not exhibit a tendency to wide variation in viscosity is essential to the process in addition to other problems which may be encountered during and after transportation of the slurry through a pipeline. Thus, agglomeration and separation of the sulfur from the carrier fluid, plating, depositing or coating of the sulfur on pipeline walls causing plugging of the pipeline, corrosion, viscosity changes due to pressure and temperature variations requiring greater pumping power which increases operation costs, etc., are only a few of the problems normally encountered in making sulfur-liquid hydrocarbon slurries for transportation through pipelines.

Although the above are serious problems for consideration in transporting sulfur through pipelines, nevertheless the transportation of sulfur in slurry form through pipelines can be made to be an effective, attractive and economic means of sulfur transportation, particularly since sulfur is recovered or obtained from isolated, remote and inaccessible areas, and must be transported to desired accessible areas. As noted above, a number of methods have been proposed for making sulfur slurries for pipeline transportation such as by injecting molten sulfur into water or a liquid hydrocarbon thereby forming a sulfur slurry and thereafter injecting the slurry into a pipeline for transportation to a terminal station. Known methods for making sulfur slurries suitable for transporting through pipelines generally do not overcome the agglomeration, deposition, sticking, coating and/or plugging problems described above. Also, it is essential that in order to avoid the sticking of sulfur to pipeline walls and plugging of the pipeline, that the slurry when injected into the pipeline be at a temperature of below 150° F. and preferably around 120° F. or lower. Since the molten sulfur is generally at around 240 to 300° F. or higher for injection into a hydrocarbon carrier, the slurry formed is substantially above the temperature required for pipeline injection and therefore must be cooled, preferably to at least

2

120° F. Therefore, slurring sulfur in oil and cooling it effectively for pipeline injection and transportation is an essential feature of the technology of sulfur-oil slurry making and cooling. Conventional cooling such as allowing the slurry to cool on standing is time consuming and costly and other means such as surface heat exchange is also costly and prone to fouling and plugging.

An object of the present invention is to prepare sulfur-liquid hydrocarbon slurries suitable for pipeline transportation.

10 Still another object of the present invention is to prepare sulfur-liquid hydrocarbon slurries which are resistant to agglomeration, deposition, sticking and plugging of equipment used in its manufacture and pipelines transporting said slurries to a terminal station.

15 Still another object of this invention is to prepare a sulfur-oil slurry in which the sulfur particles are essentially in spherical form and are resistant to attrition, separation and deposition and sticking to metal surfaces.

20 Still another object of the present invention is to prepare a sulfur-oil slurry for pipeline transportation such that it can be pumped at reduced pumping costs and requires a minimum of handling and is readily separated from the oil phase at the terminal end of the line.

25 Still another object of the present invention is to effectively cool sulfur-oil slurries to a temperature range suitable for injection into pipelines for transportation of the slurries to terminal stations.

30 Other objects will be apparent from the following description.

SUMMARY OF THE INVENTION

It has now been discovered that sulfur-liquid hydrocarbon slurries for pipeline transportation can be effectively cooled and maintained below about 150° F. and preferably around 120° F. or lower and made so that the sulfur is dispersed in the liquid hydrocarbon carrier in a stable form resistant to agglomeration, sticking and attrition by injecting molten sulfur into a suitable liquid hydrocarbon carrier ranging in viscosity from gasoline to a crude oil and preferably also adding to the carriers a small amount, preferably less than 20% based in the carrier of a vaporizable low molecular weight hydrocarbon such as an aliphatic hydrocarbon of less than 6 carbon atoms, e.g., propane, butane and pentane and mixtures thereof which on evaporation cools the sulfur-liquid hydrocarbon slurry to a temperature required for pipeline injection and transportation. Cooling the slurry by evaporation of the C₆ or lower hydrocarbon from the slurry also concentrates the sulfur slurry which can contain from 20-75% by volume of sulfur stably dispersed in the liquid hydrocarbon carrier which can range in viscosity from a light petroleum fraction such as liquefied petroleum gas (LPG), gasoline, kerosene, fuel oil, lube oil, petroleum distillates, condensates, crude oil and mixtures thereof. Preferred carriers are liquid petroleum containing at least 10% or higher of aromatics, preferably about 15-80% aromatic enriched kerosene or oil condensate fractions or crude oil containing 15-30% aromatics which include mono- and polyaromatic hydrocarbons.

65 Although the addition of volatile low molecular hydrocarbons such as butane to liquid hydrocarbon carriers such as petroleum distillates, condensates or crude oil used for making sulfur slurries by direct injection of molten sulfur into a carrier effectively cools and concentration must be kept within critical limits of from about 5% to less than 20%. Higher concentrations of said volatile hydrocarbons, e.g., butane, have an adverse effect on shape, strength and size on sulfur particles required for pipeline transportation. Thus, the presence of 25% or more of a volatile hydrocarbon in a sulfur-oil slurry has been found to produce irregular sulfur particles

which are weak susceptible to attrition and the like. On the other hand it has been found that evaporation cooling of a sulfur-liquid hydrocarbon slurry with small amounts of butane and the like effectively cools the slurry and it has no undesirable effects with respect to size, shape and strength of the sulfur particles.

The volatile hydrocarbon, e.g., butane, can be added to, admixed with or injected into any suitable liquid hydrocarbon carrier, e.g., crude oil or fractions thereof, used in making sulfur slurries. Thus, the butane can be added separately to the carrier, e.g., crude oil, and fractions thereof and the molten sulfur is injected into such a mixture or the butane can be mixed with the crude oil and fractions thereof and the sulfur injected thereafter into the liquid hydrocarbon. After the desired amount of molten sulfur has been added the butane can be evaporated from the slurry by pressure adjustments so as to effectively cool and concentrate the sulfur slurry for injection into a pipeline for transportation to a terminal station without the danger of sulfur attrition of sulfur plugging of the line. The evaporated hydrocarbon (butane) can be recovered by compression and condensation and recycled and used again if desired.

BRIEF DESCRIPTION OF THE DRAWING

The drawing illustrates the process of this invention.

Into spray or slurry vessel 26 is introduced oil via line 10 into which line can be also introduced additives via line 13 and the oil or oil-additive mixture is passed through pump 31 into valved lines 14 and/or 16, the latter of which meets recycle oil line 17. Into vessel 26 is also introduced molten sulfur via line 11, heat exchanger 25 and spray nozzle 33 which can be above or below the oil level. The vessel 26 into which the oil and molten sulfur is injected can contain a stirrer 32 so as to aid in mixing the sulfur and oil in vessel 26 which if necessary can be heated by suitable means such as by steam jacketing the vessel 26. A volatile hydrocarbon, e.g., butane, via line 12 and valved line 15 can be introduced into the valved oil lines 14, 16 and/or recycle oil line 17 and into vessel 26. After all of the molten sulfur has been added part of the volatile hydrocarbon (butane) is flashed off and removed via valved line 19 into compressor-condenser 30 and recycled, if desired, into vessel 26 via lines 12 and 15. The sulfur slurry is removed from vessel 26 via line 21 and pumped through pump 27 into a flasher 28 wherein the remainder of the volatile hydrocarbon (butane) is flashed off and removed via valved line 20 and compressed and condensed in 30 and reused as previously noted. The sulfur-oil slurry can be removed from the flasher via valved line 22 or the sulfur-oil slurry can be thickened by sending it via valved line 23 into a settler 29 wherein a thickened sulfur-oil slurry is removed via line 24 for pipeline injection and transportation and the oil recycled if desired via lines 18 and 17 into the slurry vessel 26. The slurries recovered from lines 22 and/or 24 are cool enough for pipeline transportation so as to obviate the dangers of injecting hot slurries into a pipeline as described above.

PREFERRED EMBODIMENT OF THE INVENTION

A preferred method for preparing a sulfur oil slurry for pipeline transportation comprises spraying molten sulfur (10-70%) via line 11 into a steam jacketed vessel 26 which contains crude oil added thereto via lines 10, 16 and 17 and additives added thereto via line 13, which include asphaltenes or polar-containing natural petroleum products. Butane is introduced into the vessel 26 via lines 12, 16 and 17 in an amount of between 5% and 20% and the entire mixture is agitated until the slurry is homogeneous. After all of the molten sulfur has been added some butane is flashed off from the slurry vessel 26 by pressure control and removed via line 19 thereby cooling the sulfur-oil slurry from about 140° F. to about 100° F.

The partially cooled slurry leaves the slurry vessel 26 having a sulfur content of from about 12 to about 18% and is pumped via line 21 and pump 27 into flasher 28 where essentially all of the butane is flashed off and removed via line 20 and compressed and condensed in 30 and recycled into the oil line 15 and into slurry vessel 26 via line 14 through sulfur nozzle 33 or directly into the slurry vessel via line 17. The sulfur-oil slurry is concentrated due to removal of the butane to above 20% and generally between 20% and 30% and is removed from the flasher via line 22 at a temperature of around 70° F. Instead of using only one flasher 28 as shown in the drawing, a series of flashers can be used and the slurry can be used and the slurry can be cooled in stages. To obtain a more concentrated sulfur slurry the sulfur-oil slurry line 22 can be closed and the slurry is set to settler 29 via line 23 where the slurry is allowed to settle into an oil phase which is removed via line 18 and the oil recycled into slurry vessel 26 via lines 15, 16 and 17 or via lines 15, 10 and 14. The thickened sulfur slurry is removed from settler 29 via line 24 and has a sulfur concentration above 30% and preferably between about 35 and 60% by weight which can be pumped directly into a pipeline for transportation to a terminal station.

During the preparation of the sulfur-oil slurry in vessel 26, sulfur slurry improvement additives can be introduced in amounts of from 0.1% to 10% (0.5-5%) into the oil which aid in formation of spherical sulfur particles within the range of 20 to 800 microns and which impart to the slurry other benefits. The additives best suited for this purpose include asphaltenic additives which can be obtained from unrefined or refined crude oil and fractions thereof. By unrefined crude oil is meant any crude oil which has not been processed in a refinery. Thus, a crude oil may be used as it is removed from the ground, or it may be first processed in field units such as oil-water separators, degasers, etc. Although just how the asphaltenes function in the slurry mixture is not understood, it has been found that the asphaltenes prevent sulfur agglomeration, sticking and aid in the formation of spherical sulfur particles having dimensions of from 10 to 800 microns and preferably between 100 and 700 microns.

The asphaltenes can be recovered from petroleum stocks by any suitable means such as described in the Journal of the Institute of Petroleum, February 1968, pages 50-53 and April 1968, pages 107-114 or as described in U.S. Pats. 3,206,388; 3,228,870; 3,153,623; 2,729,589; 3,368-876; 3,364,138; 3,206,388 and 3,275,076. The latter two base materials can be used per se as the asphaltene additive and carrier for the slurry. In other words high asphaltene crudes or fractions thereof containing at least 1% asphaltenes can be used both as the carrier and additive for the sulfur slurry. The asphaltenes, asphaltogenic acids and carboils and their method of recovery and separation from crudes and fractions thereof is also fully described in chapter 9 of the Sachanen's book on "The Chemical Constituents of Petroleum" and includes petroleum resins, asphaltenes, asphaltogenic acids and their derivatives. Also, the asphaltene materials described in U.S. Pats. 3,275-076; 3,284,340 or 3,336,146 can be used and they can be separated from petroleum by methods described in U.S. Pats. 3,364,138 and 3,368,876.

Instead of asphaltenes, natural surfactant components present in crude oil can be used. The natural surfactants present in the crude oil include the natural polar-containing constituents present in crude oil such as the nitrogen-oxygen- and sulfur-containing materials and active hydrocarbons possessing surfactant properties and the materials can be added to the slurry of sulfur and liquid petroleum as described prior to or during the making of the slurry or these active surfactant materials can be injected when necessary in various places along the pipeline where indications are that the slurry might cause sulfur agglomeration, deposition, sticking or plugging of the line. Any plugging detection means known in the art can be used

for this purpose. It has been noted that by adding or injecting into a slurry of the sulfur and liquid petroleum in which the sulfur content of the slurry can vary from about 10% to about 75% or higher, preferably between 30 and 70% sulfur, e.g., kerosene or oil condensate or crude oil, during or after the slurry preparation of from about 0.1 to 10% of an active surfactant material derived from crude oil, that these active surfactant materials not only prevent plugging of pipelines transporting said slurry but also preventing agglomeration of sulfur, sticking during the slurry preparation and deposition of sulfur on the walls of the pipelines and improves flow of the slurry and reduces pumping costs.

The preferred additive is asphaltene and it should be added to the oil first and the molten sulfur injected thereafter.

Oils, preferably crude oils rich in asphaltenes, can be used per se in making the sulfur slurry. Generally, the liquid petroleum carrier for the sulfur can be one ranging in viscosity from a light petroleum fraction such as liquefied petroleum gas (LPG), gasoline, kerosene, fuel oil, lube oil, petroleum distillates, condensates, crude oil and mixtures thereof. A typical crude suitable for making the sulfur slurry has the following properties shown in Tables A and B.

Tables A and B give the properties of oil suitable for sulfur slurry making the Tables 1-4 set forth the conditions for making sulfur-oil slurries in accordance with the process of the present invention.

Sulfur slurries prepared by the method of the present invention can be transported through pipelines over great distances without the danger of sulfur deposition, agglomeration, sticking or plugging of the pipelines.

At the terminal end of the line the sulfur can be removed from the liquid hydrocarbon by suitable means such as described in U.S. Pat. No. 2,809,885 or as described in the copending patent application Ser. No. 684,507, filed Nov. 20, 1967 which comprises treating oil contaminated sulfur with an aqueous solution containing a mixture of alkali hydrosulfide and corresponding hydroxide, e.g., ammonium hydrosulfide and ammonium hydroxide or by other suitable means such as sulfur can be recovered from the oil slurry by filtration of molten sulfur and liquid-liquid extraction with a hydrocarbon solvent containing 10-50% aromatic. Thus, at the receiving terminal the sulfur slurry can be filtered and washed. The recovered sulfur is then melted and purified by liquid-liquid extraction with an aromatic hydrocarbon such as cumene. Also, if desired, the filtered sulfur can be steam stripped to recover bright yellow sulfur.

The foregoing description of the invention is merely intended to be explanatory thereof. Various changes in the details of the described method may be made within the scope of the appended claims without departing from the spirit of the invention.

We claim as our invention:

1. A method of transporting cooled sulfur slurries through a pipeline to a terminal station comprising:
  - (a) injecting molten sulfur into a liquid petroleum carrier having a viscosity above liquefied petroleum gas containing a small amount of volatilizable low molecular weight hydrocarbon of less than 6 carbon atoms under pressure to form a sulfur slurry containing at least 10% sulfur by volume;
  - (b) partially evaporating the low molecular weight hydrocarbon to partially cool the slurry and to concentrate the sulfur in the slurry to at least 15% by weight;

(c) conducting the partially cooled sulfur slurry to a flasher vessel where the remainder of the low molecular weight hydrocarbon is removed and evaporation cooling and thickening the sulfur slurry to a sulfur content of above about 20% by weight; and,

(d) injecting the thickened and cooled sulfur slurry into a pipeline.

2. The method of claim 1 wherein the carrier in (a) is a liquid petroleum selected from the group consisting of petroleum distillates, petroleum condensates, crude oil and mixtures thereof to which is added a small amount of a surfactant naturally present in crude oil.

3. The method of claim 2 wherein the carrier in (a) is a crude oil and the surfactant is an asphaltenic hydrocarbon.

4. The method of claim 1 wherein the carrier (a) is a crude oil containing asphaltenes and the evaporating cooling liquid (b) is butane and the thickened sulfur slurry of (c) contains from 20 to 35% sulfur by weight.

5. The method of claim 4 wherein the thickened sulfur-asphaltenic-containing crude oil slurry is essentially free of butane.
